UNITED STATES PATENT OFFICE.

MARETON N. THOMPSON, OF ENTERPRISE, ALABAMA.

SAFETY-ENVELOP.

No. 880,936.

Specification of Letters Patent.

Patented March 3, 1908.

Application filed January 26, 1907. Serial No. 354,326.

To all whom it may concern:

Be it known that I, MARETON N. THOMPSON, a citizen of the United States of America, residing at Enterprise, in the county of 5 Coffee and State of Alabama, have invented new and useful Improvements in Safety-Envelops, of which the following is a specification.

This invention relates to safety envelops, 10 and one of the principal objects of the same is to provide an envelop of simple construction which cannot be surreptitiously opened.

Another object of the invention is to provide sealing tabs at the sides or edges of the 15 envelop, designed to be sealed inside the envelop to prevent opening without detection.

These and other objects may be attained by means of the construction illustrated in the accompanying drawings, in which:

20 Figure 1 is a face view of the addressed side of an envelop made in accordance with my invention. Fig. 2 is a rear side view of the envelop sealed. Fig. 3 is a rear side elevation of the envelop before the sealing tabs 25 have been inserted and secured in place. Fig. 4 is a plan view of the blank from which my envelop is made.

In carrying out my invention I cut out a 30 paper blank, as shown in Fig. 4, comprising a body portion 1 having side flaps 2 provided with adhesive material 3 upon one edge thereof, said flaps adapted to be bent on the lines 4 to form the envelop inclosure. Parallel slots 5 are formed in the edges of the 35 envelop, substantially in line with the folding line 4. A sealing flap 6 provided with a tab 7 is gummed, as at 8, and adapted to engage an opening 9 in the lower exterior flap 10 forming the rear side of the envelop, said flap 40 being gummed around its outer edge as at 11, and adapted to be bent upon the dotted line 12. At the sides of the flap 10 are laterally projecting tabs 13 designed to be inserted in the slots 5 at the opposite edges of 45 the envelop, said tabs being gummed upon one side, as at 14, to adhere to the inner surface of the body portion 1 of the envelop when sealed.

In making up the envelop from the blank,

shown in Fig. 4, the two side portions 2 are 50 bent inwardly upon the dotted line 4 and secured together by the gummed edge 3. The flap 10 is then secured upon the outer surface of the side flaps 2 by means of the gummed edge 11. When it is desired to seal the envelop the tabs 13 are inserted into the slots 5 after the gummed portions have been moistened, and upon slight pressure these tabs are made to adhere to the inner surface of the body portion 1. The sealing flap 6 is then 55 bent upon the dotted line 15, and the tab 7 is moistened and inserted in the opening 9 to seal the envelop.

From the foregoing it will be obvious that an envelop made in accordance with my invention cannot be opened or tampered with without easy detection. The envelop can be manufactured at slight cost, and when sealed forms a reliable and safe envelop for 60 ordinary use.

Having thus described the invention, what I claim is:

The herein described safety envelop comprising a body portion having overlapping side flaps one at each side thereof, the overlapping portion of one of said flaps being secured to the other, said side flaps and body portion having slots formed therein at two 75 points longitudinally in the edges thereof on the line of fold of said side flaps, a back portion provided with laterally extending tabs and a central aperture, said back portion being secured to the side flaps and said tabs being gummed and inserted in the slots and secured to the body portion of the envelop, and 80 a sealing flap gummed upon both of its sides and provided with a tab to be passed through the aperture in the back portion of the envelop.

In testimony whereof, I affix my signature 85 in presence of two witnesses.

MARETON N. THOMPSON.
